UNITED STATES PATENT OFFICE.

GEORGE R. FESSENDEN, OF ROCHESTER, NEW YORK, ASSIGNOR TO NORTH EAST ELECTRIC COMPANY, OF ROCHESTER, NEW YORK, A CORPORATION OF NEW YORK.

WHEEL-PULLER.

1,357,698.

Specification of Letters Patent.

Patented Nov. 2, 1920.

Application filed September 20, 1919. Serial No. 325,225.

To all whom it may concern:

Be it known that I, GEORGE R. FESSENDEN, a citizen of the United States, residing at Rochester, in the county of Monroe and 5 State of New York, have invented certain new and useful Improvements in Wheel-Pullers; and I do hereby declare the following to be a full, clear, and exact description of the invention, such as will enable 10 others skilled in the art to which it appertains to make and use the same.

This invention relates to a device for removing wheels, ball-races and the like, from the ends of shafts, and the object of the invention is to produce a simple, compact, and 15 inexpensive device capable of exerting a powerful pull against the article to be removed, and conveniently adaptable to wheels or articles of a variety of diameters and 20 forms.

To the foregoing end the invention comprises a wheel-puller in which one or more divided sleeves are used, these sleeves being formed, at their ends, for engagement with 25 the part which is to be pulled; in combination with means for clasping the parts of the sleeve against said part, and a device, such as a screw, for exerting pressure against the shaft on which the part is mounted.

30 The preferred embodiment of the invention is illustrated in the accompanying drawings, in which Figure 1 is a side-elevation of a wheel-puller with its parts in coöperative condition; Fig. 2 is a side-elevation, partly 35 in section on the line 2—2 in Fig. 1; Fig. 3 is a section on the line 3—3 in Fig. 2; and Fig. 4 is a partial side-elevation, in section on the line 2—2 in Fig. 1 but on a larger 40 scale than the latter figure, showing the wheel-puller as used to remove a ball-race from a shaft.

In the illustrated embodiment of the invention the wheel-puller comprises an outer sleeve 5, of generally cylindrical form, 45 which is divided longitudinally into two parts. At the upper end the sleeve is provided with an inwardly projecting flange producing lips 6, and at the lower end with inwardly projecting lips 7. The sleeve 5 50 constitutes means for engagement with the wheel or part which is to be pulled, and it coöperates with means for applying pressure to the shaft. These latter means comprise a body 8 which is perforated and screw-threaded to receive a screw 9. The lower

end of this screw is provided with a part 10, of reduced diameter, which engages the end of the shaft, and at its lower extremity the part 10 has a conical projection 11 adapted to enter a center-hole on the end of the shaft 60 and thereby to maintain the parts in correct alignment. The screw has a flat head 12 at its upper end, by means of which it may be turned.

The body 8 has an outwardly projecting flange 13 at its lower end, and when the puller is in position for use the two parts of the sleeve 5 are clasped around the body, so that the flange 13 is engaged and retained by the lips 6, as shown in Figs. 2 and 4, thus 70 permitting the thrust of the screw to transmit tension through the sleeve 5 and the lips 7 to the part which is to be pulled, the lips 7 at this time lying beneath or behind such part.

75 The parts are retained in the position just described by means of a ring 14, which holds the two halves together as shown in the drawings. When the puller is to be applied to, or removed from, the part which is to be pulled, the ring 14 is removed, and the halves of the sleeve may then be taken apart to permit the lips 7 to be suitably engaged with or disengaged from said part.

In order that the puller may be adapted 85 for use in pulling parts of several sizes and shapes, it is provided with a second or inner cylindrical sleeve 16, which also is divided longitudinally into two parts. At its respective extremities the sleeve 16 has inwardly projecting lips 17 and 18, one pair of these lips being greater in radial dimension than the other, so as to provide for engagement with wheels, or the like, of two 90 different diameters.

A feature of the invention resides in its adaptation for pulling the inner races of ball-bearings of the separable type, such 100 races being in the form of rings with shallow peripheral grooves. For this purpose the lips 17 and 18 are convexly rounded, as shown, so that they may engage in the groove of a ball-race 22 mounted upon a shaft 20, as shown in Fig. 4. To provide for 105 a sufficiently firm engagement between the race and the lips, two screws 21 are threaded into the sleeve 5, and by tightening these screws the two halves of the inner sleeve 16 may be pressed forcibly toward each other, thus forcing the lips 17 and 18 firmly into 110

the groove in the ball-race. With the parts so engaged the screw 9 is turned by means of a suitable wrench, and corresponding rotation of the body 8 is prevented by engagement of a second wrench with flattened surfaces 15 on the body.

It will be seen that the lips of different diameters on the sleeves 5 and 16 provide for pulling wheels or ball-races of at least 10 three different diameters, and by the provision of a greater number of inner sleeves 16, with lips of different diameters or forms, the puller may be adapted for use with parts of any desired number of forms or sizes.

15 The invention is not limited to the embodiment thereof hereinbefore described and illustrated in the accompanying drawings, but it may be embodied in various other forms within the scope of the following 20 claims.

The invention claimed is:

1. A wheel-puller comprising: a screw; a body in which the screw is threaded; a plurality of members having inward projections, 25 at their respective ends, for engaging, respectively, said body and the part which is to be pulled; and a removable ring adapted to embrace said members and to hold them in coöperative relation with said body and 30 said part.

2. A wheel-puller comprising: a divided sleeve formed, at its respective ends, for engagement with parts of different forms or sizes which are to be pulled; means for holding the members of said sleeve in coöperative 35 relation with each other; and means, coöperative with the sleeve when in either of its operative positions for applying pressure to the shaft on which is mounted the 40 part which is to be pulled.

3. A wheel-puller comprising: a plurality of divided concentric sleeves provided, respectively, with inward projections of different forms or radii for engagement with parts, of different forms or diameters, which 45 are to be pulled; a removable member encircling the outermost sleeve and acting to secure its parts together in coöperative relation, and means, coöperative with the outermost sleeve, for applying pressure to the 50 shaft on which is mounted the part to be pulled.

4. A wheel-puller comprising: a screw; a flanged body in which the screw is threaded; a longitudinally divided sleeve adapted 55 to embrace said body and having, at one end, an inward projection for engagement with the flange on the body and, at the other end, an inward projection for engagement with the part to be pulled; and means for 60 securing the members of the sleeve together in coöperative relation.

5. A wheel-puller comprising: a plurality of members formed for engagement with the part which is to be pulled; means, coöperative 65 with said members, for clasping them about said part and for applying pressure to the shaft on which said part is mounted; and a divided sleeve adapted to be embraced by said members and formed for pulling engagement with a part of different form or size from the part which said members are adapted to pull by direct engagement therewith.

6. In a wheel-puller as defined in claim 75 5, screws, carried by said members, for forcing the parts of said divided sleeve positively toward each other to cause them to engage the part to be pulled.

GEORGE R. FESSENDEN.
